(57) **CLAIM**

The ornamental design for a pinpoint metal detector, as shown and described.

DESCRIPTION

FIG. 1 is a front view of a pinpoint metal detector according to one embodiment of the present design; FIG. 2 is a rear view of the pinpoint metal detector shown in FIG. 1;

FIG. 3 is a right side view of the pinpoint metal detector shown in FIG. 1 from the right side of FIG. 1;

FIG. 4 is a left side view of the pinpoint metal detector shown in FIG. 1 from the left side of FIG. 1;

FIG. 5 is a bottom end view of the pinpoint metal detector shown in FIG. 1 from the bottom end of FIG. 1;

FIG. 6 is a top end view of the pinpoint metal detector shown in FIG. 1 from the top end of FIG. 1;

FIG. 7 is a front perspective view of the pinpoint metal detector shown in FIG. 1 from a top-left direction;

FIG. 8 is a right side perspective view of the pinpoint metal detector shown in FIG. 1 from a top-front direction;

FIG. 9 is a rear perspective view of the pinpoint metal detector shown in FIG. 1 from a rear-top direction;

FIG. 10 is a right side perspective view of the pinpoint metal detector shown in FIG. 1 from a bottom-rear direction; and,

FIG. 11 is a left side perspective view of the pinpoint metal detector shown in FIG. 1 from a bottom-rear direction. The broken lines in the figure illustrate unclaimed structure and do not constitute a part of the claimed design.
